UNITED STATES PATENT OFFICE.

WILLIAM JOSEPH QUINN, OF SARANAC, NEW YORK.

WRENCH.

SPECIFICATION forming part of Letters Patent No. 699,234, dated May 6, 1902.

Application filed September 13, 1901. Serial No. 75,347. (No model.)

To all whom it may concern:

Be it known that I, WILLIAM JOSEPH QUINN, a citizen of the United States, residing at Saranac, in the county of Clinton and State of New York, have invented a new and useful Wrench, of which the following is a specification.

My invention is an improved wrench which is adapted for use both as a nut-wrench and as a pipe-wrench; and it consists in the peculiar construction and combination of devices hereinafter described and claimed.

One object of my invention is to provide a wrench which may be readily adjusted for operation on nuts, pipes, or other objects of varying size.

A further object of my invention is to provide a wrench with an operating-lever which affords leverage and also serves to keep the jaws in operative engagement with the nut or pipe.

A further object of my invention is to provide a wrench composed of elements which may be readily assembled or disassembled and which are connected together when assembled by a single removable bolt, screw, or pin.

A further object of my invention is to provide a wrench with an operating-lever which is geared to the sliding jaw and serves to operate the sliding jaw and to also afford leverage for turning a nut or pipe with which the wrench is engaged.

A further object of my invention is to provide means for readily disengaging the said operating-lever from the sliding jaw and for adjusting the gearing between the said lever and the jaw to compensate for wear.

In the accompanying drawings, Figure 1 is a side elevation of a wrench embodying my improvement. Fig. 2 is a transverse section of the same, taken on a plane indicated by the line *a a* of Fig. 1. Fig. 3 is a detail view, partly in elevation and partly a longitudinal section, of the same.

The fixed jaw 1 of my improved wrench is provided with an arm 2, which projects from its inner side. The said arm has at a suitable distance from its inner end a circular transverse opening 3, which is of suitable diameter. A longitudinal bore 4 in the said arm 2 communicates at one end with one side of the said opening 3.

The sliding jaw 5 has a guide or arm 6, into

which the arm 2 projects, the said guide, together with the said jaw 5, being adapted to slide backward and forward on the said arm 2 to adjust said sliding jaw with relation to the fixed jaw. The upper portion 7 of the said guide 6 corresponds in width with the thickness of arm 2. The lower portion of the said guide is wider, the said lower portion of said guide projecting laterally beyond the opposite sides of the said arm 2, and on each of the said projecting portions of the lower side of the said guide is formed a rack 8, having serrated teeth 9. The shoulders 10 are formed at the outer end of the said racks on opposite sides of the said guide.

An eccentric 11 is fitted in the opening 3 of the arm 2 and is adapted to partly rotate therein. The said eccentric has a notch or recess 12 in one side of its periphery, which notch or recess is adapted to be engaged by a spring-pressed bolt 13, which is disposed in the bore 4. The operating-lever 14 has its inner end forked or bifurcated to form the arms 15, which are disposed astride of the arm 2 and the narrow upper portion 7 of the guide 6. At the inner ends of the said arms 15 are formed gear-segments 16, the teeth of which are serrated and adapted to engage those of the racks 8. A bolt, screw, or pin 17 is passed through openings in the arms 15, which openings are centrally disposed with reference to the gear-segments 16, and the said bolt, screw, or pin is passed through an opening which is disposed eccentrically in the eccentric 11. The said bolt, screw, or pin serves to pivot the operating-lever 14 to the arms 2, so that when the gear-segments 16 are in engagement with the racks 8 the sliding jaw 5 may be by means of the said lever 14 moved toward or from the fixed jaw 1 to enable the said jaws to engage a nut, pipe, or other object to be turned by the wrench. It will be understood that the lever 14, which is thus geared to the sliding jaw, serves not only to operate the said sliding jaw, but also to afford leverage by which the wrench may be operated to turn or hold the nut, pipe, or other objects on which it is employed. By turning the eccentric through a partial rotation in the opening 3 the pivot 17, and hence the lever 14, may be moved sufficiently to disengage the gear-segments 16 from the racks

8 in order that the sliding jaw 5 may be adjusted as may be required to adapt the wrench to be used in connection with nuts or other objects of varying sizes. When the said segments 16 are in engagement with said racks 8, the spring-pressed bolt 13, which engages the eccentric, prevents the latter from being turned in ordinary usage, and hence the said operating-lever 14 is kept geared to the sliding jaw 5; but by jerking upwardly in the direction of its length on the said operating-lever 14, or by hammering the head of the fixed jaw 1 on an object, or by striking the lever 14 against the shoulders 10 the eccentric 11 may be started, notwithstanding the spring-pressed locking-bolt, and turned to the extent required to disengage the lever gear-segments from the racks of the sliding jaw, as will be understood.

20 It will be understood that as the gear-segment 16 and the racks 8 wear the eccentric 11 will turn in the opening 3 to compensate for the wear of the said parts, and hence the lever 14 will be kept geared to and in operative relation with the sliding jaw.

25 The inner sides of the jaws 1 5 are fretted or serrated to enable the same to readily grasp a round object, such as a pipe, when the wrench is used as a pipe-wrench.

30 It will be understood that by turning the operating-lever 14 in the position shown in Fig. 1 the wrench can be used in a space equal to only half the normal length of the wrench, which is a matter of great importance where the work must be performed in a contracted space.

Having thus described my invention, what I claim is—

1. In a wrench, the combination of a fixed 40 jaw having an arm, a sliding jaw on said arm, and a lever pivotally supported by said arm and geared to said sliding jaw to operate the latter, the said lever also serving as the handle for operating the wrench, substantially as described.

2. In a wrench, the combination of a fixed 45 jaw having an arm, a sliding jaw guided on said arm and having a rack, and an operating-lever pivoted to said arm and having a gear engaging said rack, to operate said sliding jaw, said operating-lever also serving as the handle for operating the wrench, substantially as described.

3. In a wrench, the combination of a fixed 55 jaw having an arm, a sliding jaw having a rack, an operating-lever pivotally connected to said arm and having a gear engaging said rack, and means to shift said gear out of engagement with said rack to enable said sliding jaw to be adjusted, for the purpose set forth, substantially as described.

4. In a wrench, the combination of a fixed 60 jaw having an arm, a sliding jaw carried by said arm, an operating-lever pivoted to said arm, connections between said operating-lever and said sliding jaw, and means to dis-

connect said operating-lever from said sliding jaw, to enable the latter to be adjusted, independently of said lever, with relation to said fixed jaw, substantially as described.

5. In a wrench the combination of a fixed 70 jaw having an arm, a sliding jaw carried by said arm, an operating-lever, pivoted to said arm and connected to said sliding jaw, to actuate the latter, and means to shift the pivot of said operating-lever and thereby disconnect the same from said sliding jaw, for the purpose set forth, substantially as described.

6. In a wrench, the combination of a fixed 75 jaw having an arm, a sliding jaw, carried by said arm, an eccentric seated in an opening in said arm an operating-lever pivoted to said eccentric, said sliding jaw and said operating-lever having gears adapted to engage each other, said eccentric enabling the pivot of 80 said operating-lever to be shifted, to disengage said gears and to compensate for the wear thereof, substantially as described.

7. In a wrench, the combination of a fixed 85 jaw having an arm, a sliding jaw, a pivoted operating-lever, connections between the latter and the sliding jaw, means to shift the pivot of said lever to disengage the same from said sliding jaw, and means to lock said pivot-shifting means, substantially as described.

95 8. In a wrench, the combination of a fixed jaw having an arm provided with an opening, a sliding jaw carried by said arm, said sliding jaw having a rack, an eccentric mounted in the opening of said arm, an operating-lever having its pivot carried by said eccentric, and a gear with which said operating-lever is provided, said gear engaging said rack, substantially as described.

9. In a wrench, the combination of a fixed 100 jaw having an arm provided with an opening, a sliding jaw carried by said arm, said sliding jaw having a rack, an eccentric mounted in the opening of said arm, an operating-lever having its pivot carried by said eccentric, 105 a gear with which said operating-lever is provided, said gear engaging said rack, and means to lock said eccentric against rotation, substantially as described.

10. In a wrench, the combination of a fixed 110 jaw having an arm provided with an opening, a sliding jaw carried by said arm, said sliding jaw having a rack, an eccentric mounted in the opening of said arm, and having a peripheral notch, an operating-lever having its 115 pivot carried by said eccentric, and said operating-lever having a gear engaging said rack, and a spring-pressed bolt to engage the notch of said eccentric and lock the latter against rotation, substantially as described.

120 In testimony that I claim the foregoing as my own I have hereto affixed my signature in the presence of two witnesses.

WILLIAM JOSEPH QUINN.
